UNITED STATES PATENT OFFICE.

JOHN L. CARTMELL, OF COLUMBUS, OHIO.

METALLIC RAILROAD TIE AND RAIL CLAMP THEREFOR.

Application filed April 3, 1928. Serial No. 267,077.

The present invention relates to railroad ties, and has for its principal object to provide an article of this character constructed of metal and to provide means arranged 5 thereon for fastening the rail in position upon the tie.

A further object of the invention is to provide a hollow metallic railroad tie adapted to support a pair of rails upon its upper face, 10 and forming the portion of the tie immediately beneath the rail of a solid construction, whereby to increase the strength of the tie at that portion subjected to the most strain.

A still further object is to provide an article of this character of a simple and practical construction, which is strong and durable, in which the weight of the tie is materially reduced, which is comparatively inexpensive to manufacture, permits of the ready placing 20 and removal of the rail in position thereon, and which is otherwise well adapted for the purposes for which the same is intended.

Other objects and advantages reside in the special construction and combination of the 25 various elements comprising the invention, reference being had to the accompanying drawings, forming a part thereof, wherein:

Figure 1 is a top plan view of a tie, constructed in accordance with my invention 30 and showing a pair of rails secured in position thereupon.

Figure 2 is a side elevational view thereof.

Figure 3 is a longitudinal sectional view, taken substantially along the line 3—3 of 35 Figure 1.

Figure 4 is a vertical sectional view, taken along the line 4—4 of Figure 2.

Figure 5 is a similar view, taken along the line 5—5 of Figure 3, and

Figure 6 is a perspective view of one of the rail clamping plates.

Referring now to the drawing in detail, the invention comprises a railroad tie, constructed of metal and of a hollow formation. A 45 pair of rails 5 are adapted to seat upon the top 6, of the tie, adjacent the ends thereof, the outer flange 7 of each of the rails being engaged by upwardly and inwardly inclined lugs 8, cast integrally with the tie and formed 50 at the side edges of the top portion 6 thereof.

The center portion of the tie, between the rails 5 has its top portion open, as shown at

9, and with the sides 10 adjacent such opened portions, reduced in height as is shown at 11.

The inner flange 12 of each of the rails 5 is engaged by a flanged edge 13, formed on a retaining plate 14, adapted to seat upon the top portion 6 of the tie, along the edge of the opening 9, formed in the top and at each end thereof. The plates 14 and the top portion 6 of the tie are provided with aligned openings 15, through which bolts 16, may be inserted for securing the plates in a fixed position upon the tie, so as to secure the rail against movement thereon.

The portion of the tie immediately beneath the rails 5 is constructed in a solid formation as shown at 17, whereby to provide a reinforced foundation for the rails. In this manner, sufficient strength is provided for bearing the weight of the train as the same passes over the rails and at the same time permit of considerable economy in the construction of the tie, which otherwise is of a hollow formation.

It is obvious that the invention is susceptible of various changes and modifications, without departing from the spirit or scope of the invention or sacrificing any of its advantages, and I accordingly claim all such forms of the device, to which I am entitled.

Having thus described my invention, what I claim as new is:

In combination, a metallic railroad tie of hollow formation at its end portions and at 85 its center and adapted to support a pair of rails upon its upper surface and with the upper portion of the tie between the rails open, said tie being of a solid construction at the portion thereof immediately beneath the 90 rails, a pair of rail flange engaging lugs formed integrally with the tie and adapted to engage the outer flange of each of said rails, a rail attaching plate engaging the inner flange of each of said rails, and bolts upwardly 95 through the portion of the upper surface of the tie, adjacent the solid construction thereof for securing the plates in position, said tie having its side walls between the rails reduced whereby to afford access to said bolts 100 for working the bolts of the rail from a position between the rails.

In testimony whereof I affix my signature.

JOHN L. CARTMELL.
